POSITIONING MEANS FOR CLIPPER BLADE

Leo J. Wahl, Sterling, Ill., assignor to Wahl Clipper Corporation, Sterling, Ill., a corporation of Illinois

Application October 29, 1952, Serial No. 317,486

6 Claims. (Cl. 30—223)

My invention relates to a positioning means for a clipper blade, and more particularly to a positioning means for the stationary blade of an electric hair clipper.

An electric hair clipper includes a casing and a pair of clipper blades mounted at the forward end of the casing. One of the clipper blades is movable, that is, it is driven back and forth by an electromagnet and armature positioned within the casing. The other blade is stationary during clipper operation, and the upper surface thereof forms a bearing for the lower surface of the movable blade.

The stationary blade may be mounted directly on the casing, as here illustrated, or it may be mounted on a plate which is adjustable whereby the length of cut provided by the clipper may be varied. Examples of this latter arrangement are shown in my prior U. S. Patents Nos. 1,895,183 and 2,265,880 where the stationary blade is carried respectively by U-shaped member 12 and bracket 23.

For purposes of this application, the part of the clipper to which the stationary blade is attached will be referred to as a mounting portion, and it is to be understood that the mounting portion contemplates *inter alia* either a part of the casing itself or some intermediate bracket member which provides adjustability.

The movable blade of a clipper usually occupies a position with reference to the clipper casing which is determined by the location and size of the armature within the casing and the linkage arrangement extending between the armature and the blade. Since the armature location and size and the linkage arrangement usually are not subject to adjustment, the location of the movable blade is non-adjustable with respect to the clipper casing.

In order to obtain satisfactory clipper operation, the stationary blade must occupy a proper position with respect to the movable blade. Also, it is necessary that the stationary blade be removed from the clipper from time to time by the ultimate user for cleaning or other maintenance. Therefore, it is desirable to provide means whereby the stationary blade may be removed and replaced by a non-expert without disturbing the factory-set critical relationship between the respective blades.

One object of this invention, therefore, is to provide means for positioning the stationary blade of a clipper which can be accurately set by the clipper manufacturer, and which will permit simple removal and replacement of the blade by the ultimate user without disturbing the factory setting.

The invention utilizes an intermediate means which is attached to the mounting portion of the clipper, and which accurately may be positioned thereon by the clipper manufacturer. The stationary clipper blade in turn is positioned on the mounting portion by the intermediate means, and it may readily be removed and replaced by the ultimate user, the intermediate means being effective to insure that the stationary blade is replaced in the same position it occupied when it left the factory.

Other objects and advantages of the invention will be

2

apparent as the description proceeds, reference being had to the accompanying drawing which illustrates two structural forms of the invention. It is to be understood, of course, that in commercial applications of the invention various details might well vary somewhat from those here shown and described.

In the drawing:

Fig. 1 is a side elevational view, partly in section on line 1—1 of Fig. 2, of the forward end of a clipper embodying the invention;

Fig. 2 is a bottom view, partly in section, of the clipper portion shown in Fig. 1;

Fig. 3 is a sectional view on line 3—3 of Fig. 2;

Fig. 4 is a side elevational view, partly in section on line 4—4 of Fig. 5, of the forward end of a clipper embodying a modified form of my invention;

Fig. 5 is a bottom view, partly in section, of the clipper portion shown in Fig. 4;

Fig. 6 is a sectional view on line 6—6 of Fig. 5, and

Fig. 7 is a perspective view of a plate member used in the modified form of the invention.

Referring now to Figs. 1—3, my invention is shown embodied in the forward end of a clipper 10 which has an outer casing 11. The lower forward end of casing 11 constitutes a mounting portion 12 (Figs. 1 and 3). Within casing 11 is an armature or other drive element 14 (Fig. 1) which is connected by linkage 15 to a movable blade 16.

A stationary blade 20 is attached to mounting portion 12, and it will be noted in Fig. 1 that the upper surface of blade 20 forms a bearing for the lower surface of movable blade 16 which travels back and forth during clipper operation.

The rear portion of stationary blade 20 is provided with a plurality of openings 22, best shown in Fig. 3, there being four such openings in the form of the invention there illustrated. The diameter or size of openings 22 is large compared with the shank size of presently to be described screws which extend through the respective openings.

The middle two openings 22, when blade 20 is secured to mounting portion 12, cooperate with intermediate means which in this form of the invention comprise spaced cylindrical members 23. The external diameter or size of cylindrical members 23 corresponds with that of the middle two blade openings 22, as shown in Figs. 1—3.

The intermediate means or cylindrical members 23 have spaced openings 24 therethrough, and headed screws 25 extend through these openings into threaded relation with mounting portion 12. The shanks of screws 25 are small in size compared with openings 24 in the cylindrical members whereby the latter may be adjustably positioned on mounting portion 12 by the clipper manufacturer. When proper position is obtained, screws 25 are tightened to more or less permanently lock the members 23 to mounting portion 12. The location of members 23, of course, provides permanent orientation of stationary blade 20, yet permits the latter to be readily removed and replaced.

It will be noted in Figs. 1 and 3 that cylindrical members 23 and associated heads of screws 25 are disposed between the surface planes of stationary blade 20. This countersunk arrangement suggests to the ultimate user that screws 25 should not be disturbed.

Headed screws 28 extend through the outside blade openings 22 into threaded relation with mounting portion 12. The shanks of screws 28, as in the case of screws 25, are small in size compared with the openings 22 through which they extend, as best shown in Fig. 3. The screws 28 are the ones which secure stationary blade 20 to mounting portion 12 and which may be withdrawn by the ultimate user when it is desired to remove blade

20 for cleaning or other maintenance. When blade 20 is replaced by fitting the central openings 22 over the factory positioned cylindrical members 23, the screws 28 are reapplied and tightened to secure the blade. Such blade removal and replacement can occur an indefinite number of times without disturbing the critical factory positioning.

Referring to Figs. 4-7, a modified form of the invention utilizes a plate 30 (Fig. 7) as the intermediate means. Plate 30 has spaced openings 31 therethrough, and it is secured to mounting portion 33 of the clipper by means of headed screws 34. Openings 31 are large in size compared with the shanks of screws 34 which pass therethrough.

The forward edge of plate 30 is irregular in shape, and in the form shown has a pair of forwardly extending protuberances or lugs 36.

A stationary blade 38 has a rear edge which matches the irregular forward edge of plate 30, and the two edges abut, as shown in Fig. 5. Thus, the rear edge of blade 38 has recesses which receive lugs 36, thereby fixing the position of blade 38 with respect to plate 30.

Blade 38 has spaced openings 40, and headed screws 41 extend through the openings into threaded relation with mounting portion 33. Again, the shanks of screws 41 are small in size compared with the size of openings 40.

In this modified form of the invention, plate 30 is positioned by the clipper manufacturer and screws 34 are tightened more or less permanently. Removal of stationary blade 38 is accomplished by removing screws 41, after which the blade may be replaced by reapplying screws 41. Plate 30 with its irregular edge, of course, is effective to insure that blade 38 is replaced in proper position relative to the movable clipper blade.

From the above description it is thought that the construction and advantages of my invention will be readily apparent to those skilled in the art. Various changes in detail may be made without departing from the spirit or losing the advantages of the invention.

Having thus described my invention, what I claim as new and desire to secure by Letters Patent is:

1. In a hair clipper having a mounting portion which carries a stationary, removable blade: means for adjustably positioning said blade on said portion comprising intermediate means having spaced openings therethrough, a headed screw extending through each opening into threaded relation with said portion, the shank of each screw being small in diameter compared with the diameter of the opening through which it extends, whereby said intermediate means may be adjustably located on said portion prior to tightening said screws, said blade engaging said intermediate means whereby the latter positions the former on said mounting portion and having at least one opening therethrough, and a headed screw extending through said last named opening into threaded relation with said portion, the shank of said last named screw being small in diameter compared with the diameter of the opening through which it extends.

2. In a hair clipper having a mounting portion which carries a stationary, removable blade: means for adjustably positioning said blade on said portion comprising spaced members each having an opening therethrough, a headed screw extending through each opening into threaded relation with said portion, the shank of each screw being small in diameter compared with the diameter of the opening through which it extends, whereby said spaced members may be adjustably located on said por-

tion prior to tightening said screws, said blade engaging said spaced members whereby the latter position the former on said mounting portion and having spaced at least one opening therethrough, and a headed screw extending through said last named opening into threaded relation with said portion, the shank of said last named screw being small in diameter compared with the diameter of the opening through which it extends.

3. In a hair clipper having a mounting portion which carries a stationary, removable blade: means for adjustably positioning said blade on said portion comprising spaced cylindrical members, a headed screw extending through each cylindrical member into threaded relation with said portion, the shanks of said screws being small in diameter compared with the internal diameters of said members, said blade having spaced openings therethrough, some of said openings receiving said cylindrical members whereby the latter position said blade on said portion, and a headed screw extending through another of said openings into threaded relation with said portion, the shank of the last named screw being small compared with the opening through which it extends.

4. In a hair clipper having a mounting portion which carries a stationary, removable blade: means for adjustably positioning said blade on said portion comprising spaced cylindrical members, a headed screw extending through each cylindrical member into threaded relation with said portion, the shanks of said screws being small in diameter compared with the internal diameter of said members, said blade having spaced openings therethrough, some of said openings receiving said cylindrical members whereby the latter position said blade on said portion, and a headed screw extending through another of said openings into threaded relation with said portion, the shank of the last named screw being small compared with the opening through which it extends, said cylindrical members and associated screw heads being disposed between the surface planes of said blade.

5. In a hair clipper having a mounting portion which carries a stationary, removable blade: means for adjustably positioning said blade on said portion comprising a plate having spaced openings therethrough and an irregular edge, a headed screw extending through each opening into threaded relation with said portion, the shank of each screw being small compared with the opening through which it extends, said blade having spaced openings therethrough and an edge keyed to the irregular edge of said plate, and a headed screw extending through each blade opening into threaded relation with said portion, the shank of each last named screw being small compared with the opening through which it extends.

6. In a hair clipper having a mounting portion which carries a stationary, removable blade: means for adjustably positioning said blade on said portion comprising a plate having spaced openings therethrough and a protuberance extending from one edge, a headed screw extending through each opening into threaded relation with said portion, the shank of each screw being small compared to the opening through which it extends, said blade having spaced openings therethrough and an edge having a recess into which said protuberance extends, and a headed screw extending through each blade opening into threaded relation with said portion, the shank of each last named screw being small compared with the opening through which it extends.
